DESIGN FOR A NAPKIN CONTAINER

Morris Wieseneck, Arverne, Long Island, N. Y.

Application April 19, 1934, Serial No. 51,450

Term of patent 7 years

To all whom it may concern:

Be it known, that I, MORRIS WIESENECK, a citizen of the United States, residing at Arverne, L. I., in the county of Queens and State of New York, have invented a new, original, and ornamental Design for a Napkin Container, of which the following is a specification, reference being had to the accompanying drawing, forming a part thereof, and in which:

This design consists of a generally triangular thin-walled container which may be suspended vertically from a loop at the center of its rear edge or disposed horizontally upon feet on its bottom.

I claim:—

The ornamental design for a napkin container, as shown and described.

MORRIS WIESENECK.
